GAS TREATMENT

Clyde B. Faverty, Chicago, Ill., assignor to
Mark C. Bates, Chicago, Ill.

Application December 15, 1932, Serial No. 647,392

11 Claims. (Cl. 48—213)

My invention relates in general to gas treatment. It relates more in particular to an improved gas product, the method of producing the same and apparatus with which the method is carried on.

In industrial utilization of commercial gas such as water gas, furnace gas and other combinations and mixtures of gas, there are times when the gas is not sufficiently rich in certain respects for the proper carrying on of the process. When gas is used for producing a relatively high temperature, for example, the maximum temperature possible is often substantially equivalent to the maximum theoretical temperature obtainable with the particular gas employed. If there is the slightest deviation from theoretical calculations, the temperature produced will be below requirements and the process utilizing the high temperature will suffer proportionately. Similarly, when a certain type of furnace atmosphere is to be maintained with a given gas product, any slight deviations in the character of the commercial gas will have a detrimental effect upon the furnace atmosphere. In the use of gas for carburizing purposes, a gas having a relatively great carbon content is required and ordinary gases utilized for this purpose are sometimes either deficient in carbon or carry the carbon in such a form as to prevent its being utilized to its fullest extent in the process. My invention, therefore, relates to enriching substantially any type of commercial gas by increasing the B. t. u. content thereof and also the available carbon content.

The principal object of my invention is the provision of an improved gas supply.

Another object is the provision of an improved method of and means for enriching standard types of combustible gas.

Another object is the provision of such a method in which the gas itself may be utilized as a control.

Other objects and features of the invention will be apparent from a consideration of the following detailed description, taken with the accompanying drawing, wherein the single figure shows apparatus with which the method may be practiced.

In general, the method which I employ comprises vaporizing a liquid hydrocarbon by passing through a container hot products of combustion whereby the sensible heat of such products of combustion is effective to entrain and vaporize portions of the liquid approaching molecular size to produce a hydrocarbon vapor.

The gas to be enriched is forced under pressure through an aspirator apparatus to which the vaporized hydrocarbon is delivered whereby the vaporized hydrocarbon is drawn into the stream of gas to be enriched in proportions controlled to obtain the proper amount of increased combustible matter and/or hydrocarbon content. In the preferred form, the gas which is to be burned to provide hot gases for the vaporization of the liquid hydrocarbon is withdrawn from the apparatus immediately after the gas has been enriched, whereby the enriched mixture is burned in the manner and for the purpose described.

Referring now to the drawing, I provide a vapor chamber 10 to which fuel is supplied by a line 11 leading from a float chamber 12, the float chamber being connected by a pipe 13 to a storage tank 14, a sediment bulb 16 being interposed in the line. A balance line 17 is connected to the top of the vapor chamber and to the top of the float whereby to maintain a uniform pressure in the float chamber and vapor chamber.

A passageway 17a leads from the top of the vapor chamber to a Venturi tube 18 forming part of an aspirator, a forcing nozzle 19 being connected to the Venturi tube to withdraw vapor from the passageway 17a. A butterfly type of valve 21 is interposed to control the amount of vapor delivered to the aspirator.

A pipe 22 extending through the wall of a manifold 23 connected to the aspirator withdraws gas therefrom and delivers the same to a pilot burner 24. This pilot burner is formed to produce a mixture of air and the gas withdrawn through the pipe 22 and includes a forcing nozzle 26 formed on the end of the pipe 22 and extending into the burner 24, the burner being shaped around the forcing nozzle with a plurality of openings 27 for admitting air to produce a combustible mixture. This combustible mixture is burned at the burner tip 24a and the products of combustion are delivered through a passageway 28 to a point below the level of liquid in the vapor chamber. This level is indicated by the dotted line. The lower end of the pipe or passageway 28 is provided with a perforated plate 29 which separates the hot gases and allows them to bubble up through the holes in the bubble plate 29 and through the body of liquid hydrocarbon. It is the sensible heat from these gases and possibly to some extent also the speed of movement of the gases which causes the vaporization of the liquid hydrocarbon.

The burner nozzle or tip 24a is covered by a sealing ring 31 adapted to be withdrawn to per-

mit lighting the pilot burner. I also provide a valve 32 in the pipe line 22 to control, if necessary, the amount of gas delivered to the pilot burner. In general, I prefer to vaporize the fuel entirely by sensible heat of the products of combustion of the pilot burner and depend upon utilizing a slightly greater amount of enriching mixture if a more than usual carbon content is required.

10 The forcing nozzle 19 is connected by a pipe 33 with a blower 34, the blower withdrawing gas from a line 36 connected with a main gas line 37. A valve 38 may be interposed in the line, if necessary.

15 As an example of the use of my invention, it may be stated that ordinary "city gas" will be found to contain from 250 to 500 B. t. u. per cubic foot. Vaporized hydrocarbon, when produced by the method which I employ, contains 20 approximately 4000 B. t. u. per cubic foot. A satisfactory mixture of the two gases sufficient in B. t. u. and carbon content for most purposes is ten parts of the ordinary city gas with one part of the vaporized hydrocarbon. Assume the use of a 25 city gas of 350 B. t. u. per cubic foot. This mixture then would yield a combination gas having a B. t. u. content of approximately 700 per cubic foot. This type of gas will increase the maximum temperature obtainable very considerably and is 30 very valuable when utilized with processes that require a relatively very high temperature. Even when the maximum temperature is not required, it provides a working range in which even under the most adverse conditions a sufficiently high 35 temperature is always obtainable. For carburization processes, it is readily apparent that the vaporized hydrocarbon having a relatively high carbon content will provide a readily available source of carbon in sufficiently great proportions 40 even when combined in the proportions set out so that carburizing processes can be carried on more readily, more cheaply and with more satisfactory results.

Reference is hereby made to my copending application, Serial No. 647,391, filed December 15, 1932, which contains claims to apparatus described and shown in the present application but not claimed herein.

I have described my invention in detail to permit those skilled in the art to practice the same. 50 I do not limit myself, however, to the specific details described, the invention being limited only by the scope of the appended claims.

What I claim as new and desire to protect by 55 Letters Patent of the United States is:

1. A method of enriching commercial supplies of a combustible gas which comprises burning a combustible mixture, passing the hot gas of such combustion through a body of liquid hydrocarbon 60 to vaporize a portion thereof, forcing the combustible gas to be enriched through a constricted space and delivering thereto the vaporized hydrocarbon whereby to cause the vaporized hydrocarbon to be entrained in the combustible gas and 65 to be thoroughly admixed therewith.

2. A method as defined in claim 1, wherein the enriched gas is withdrawn, mixed with air and then burned to produce hot gases which are employed to effect the vaporization of the liquid 70 hydrocarbon.

3. A method of enriching commercial supplies of a combustible gas which comprises vaporizing a liquid hydrocarbon, and aspirating the resulting vapors by means of a stream of the combustible gas to be enriched whereby a thorough com-

mingling of the combustible gas and the hydrocarbon vapor is effected, the process being continuous and the heat serving to vaporize additional amounts of liquid hydrocarbon being generated by burning a minor proportion of the mixture of combustible gas and vaporized hydrocarbon.

4. A method of enriching commercial supplies of a combustible gas which comprises burning a portion of said gas to provide hot gaseous products of combustion, passing said hot gases of combustion into intimate contact with a proportion of liquid hydrocarbon greater than can be vaporized by said hot gases of combustion whereby a portion only of said liquid hydrocarbon is 10 vaporized, and withdrawing the resulting vapors and commingling said vapors with the combustible gas to be enriched.

5. A method of enriching commercial supplies of a combustible gas which comprises maintaining a pool of a liquid hydrocarbon in a chamber, passing hot gases of combustion beneath the surface of said pool of liquid hydrocarbon whereby vaporization of a part only of said liquid hydrocarbon is effected proportioned to the amount of 20 hot gases passing therethrough, intimately commingling the vaporized liquid hydrocarbon with the combustible gas to be enriched, withdrawing a minor proportion of said mixture and then 25 burning it to provide hot gases of combustion the hot gases of said latter combustion being utilized to effect the vaporization of additional amounts 30 of the liquid hydrocarbon.

6. A method of enriching commercial supplies of a combustible gas which comprises maintaining a pool of a liquid hydrocarbon in a chamber, passing hot gases of combustion beneath the surface of said pool of liquid hydrocarbon whereby vaporization of a part only of said liquid hydrocarbon is effected proportioned to the amount of 35 hot gases passing therethrough, and intimately commingling the vaporized liquid hydrocarbon with the combustible gas to be enriched.

7. A method of enriching commercial supplies of a combustible gas which comprises providing 45 an excess of a liquid hydrocarbon, passing hot gases of combustion into intimate contact with said liquid hydrocarbon whereby vaporization of a part only of said liquid hydrocarbon is effected proportioned to the amount of hot gases contacted therewith, intimately commingling the vaporized liquid hydrocarbon with the combustible gas to be enriched, withdrawing a minor 50 proportion of said mixture and then burning it to provide hot gases of combustion, the hot gases 55 of said latter combustion being utilized to effect the vaporization of additional amounts of the liquid hydrocarbon.

8. A method of enriching commercial supplies of a combustible gas which comprises providing a 60 liquid hydrocarbon, passing hot gases of combustion into contact with said liquid hydrocarbon whereby vaporization thereof is effected, intimately commingling the vaporized liquid hydrocarbon with the combustible gas to be enriched, withdrawing a minor proportion of said mixture 65 and then burning it to provide hot gases of combustion, the hot gases of said latter combustion being utilized to effect the vaporization of additional amounts of the liquid hydrocarbon.

9. A method of enriching commercial supplies of a combustible gas which comprises providing an excess of a liquid hydrocarbon, passing hot gases of combustion into intimate contact with said liquid hydrocarbon whereby vaporization of 75

a part only of said liquid hydrocarbon is effected proportioned to the amount of hot gases contacted therewith, and intimately commingling the vaporized liquid hydrocarbon with the combustible gas to be enriched.

10. A method of enriching commercial supplies of a combustible gas which comprises providing hot gases resulting from a combustion of combustible material, intimately contacting a regulated amount of said hot gases with a quantity of a liquid hydrocarbon whereby vaporization of a portion only of the liquid hydrocarbon is effected, intimately commingling the hydrocarbon vapors with the combustible gas to be enriched, burning only a small amount of said mixture in a pilot burner to provide hot gases of combustion and utilizing said hot gases to vaporize additional quantities of liquid hydro-

carbons, the vaporization of the liquid hydrocarbon being continuous and being effected, at least after initiation of the process, by the intimate contact of hot gases of combustion with an amount of liquid hydrocarbon in excess of that which can be vaporized by said gases.

11. A method of enriching commercial supplies of a combustible gas which comprises providing hot gases resulting from a combustion of combustible material, intimately contacting a, 10 regulated amount of said hot gases with a quantity of a liquid hydrocarbon whereby vaporization of a portion only of the liquid hydrocarbon is effected, and intimately commingling the hydrocarbon vapors with the combustible gas to be 15 enriched.

CLYDE B. FAVERTY.
